FROSTPROOF HYDRANT

Miroslav Uroshevich, Cincinnati, Ohio, assignor to
Murdock Inc., Cincinnati, Ohio

Filed May 13, 1971, Ser. No. 143,287

Term of patent 14 years

Int. Cl. D23—01

U.S. Cl. D23—12

FIG. 1 is a perspective view of a frostproof hydrant embodying my design;

FIG. 2 is a side elevational view thereof;

FIG. 3 is a rear elevational view thereof;

FIG. 4 is a top plan view thereof;

FIG. 5 is a bottom plan view thereof, with a portion of the handle broken away;

FIG. 6 is a sectional view taken on the line 6—6 in FIG. 3; and

FIG. 7 is a sectional view taken on the line 7—7 in FIG. 3.

I claim:

The ornamental design for a frostproof hydrant, as shown.
